UNITED STATES PATENT OFFICE.

WILLIAM PARKER, OF BROOKLYN, NEW YORK.

DESIGN FOR A WATCH-CASE.

SPECIFICATION forming part of Design No. 19,526, dated December 24, 1889.

Application filed March 21, 1889. Serial No. 304,232. Term of patent 7 years.

To all whom it may concern:

Be it known that I, WILLIAM PARKER, a citizen of the United States, residing at Brooklyn, in the county of Kings and State of New York, have invented a new Design for Watch-Cases, of which the following is a specification.

The design which is the subject of this invention is illustrated by the accompanying drawings, in which the similar parts in the several views are designated by similar letters.

Figure 1 is a plan view of my design, and Fig. 2 a sectional view through the line $x x$ of Fig. 1.

A denotes a conventional star having

points c , in the center of which a diamond or other ornament D may be placed. Within the points of the conventional star is the triangular and rounded ornamentation B, the whole presenting the appearance of a rosette. The star A and ornamentation B are in relief.

What I claim as my invention, and desire to secure by Letters Patent, is—

The design for a watch-case, substantially as herein described and shown.

New York city, March 19, 1889.

WILLIAM PARKER.

In presence of—

HENRY E. EVERDING,
JAMES J. COSGROVE.
